CATHODE STRUCTURE

Louis A. Williams, Belmont, Mass., assignor to
 Raytheon Manufacturing Company, Newton,
 Mass., a corporation of Delaware

Application May 26, 1948, Serial No. 29,312

14 Claims. (Cl. 250—27.5)

1
 This invention relates to cathode structures, and more particularly to an indirectly-heated cathode for electron discharge devices of the so-called magnetron type.

It has been found advantageous to use, in modern high-power tubes of the type referred to, cathodes which utilize the electron-emitting properties of thoria (thorium oxide), since emitters of this material can readily provide the copious electron emission so necessary for tubes of high power. However, electron emitters of thoria must be run or operated at rather high temperatures, on the order of 1500° C. for example, in order for them to function effectively and efficiently.

In prior art structures, in order to obtain temperatures of this order at the emitting surface, it was necessary to run or operate the heater itself at a much higher temperature, one on the order of 2500° C. or even higher. The necessity for this was due in part to the high rate of conduction of heat, away from the emitting surface, by adjoining or adjacent metallic surfaces, and due in part, if insulated heater wires were used, to the relatively poor heat-conducting characteristics of the insulating coating.

These very high temperatures at which it was necessary to run the heater, in prior art structures, shortened the life of such heaters to a substantial extent, and produced other deleterious and undesirable effects on such heaters. It has been found that insulated heater wires are impractical for such applications, since the insulating coating will not effectively withstand such temperatures for a sufficiently long period of time. If bare heater wires are used, they will start to sag in a very short time when operated at such high temperatures, and this is very undesirable, since they then come into contact with their cathode sleeves and cause short-circuits.

In addition, if the heater of a magnetron is supplied with alternating current, vibrations of such heater can be produced, as a result of the interaction of the heating current with the magnetic field necessarily existing in the magnetron. Such vibrations are undesirable for several reasons, and it is therefore necessary to so support the heater as to substantially prevent vibrations thereof.

Accordingly, the principal object of this invention is to devise an indirectly-heated cathode structure for magnetrons which has a long usable life, on the order of 500 hours for example, even when operated at a high temperature in

tubes of high power, and a structure which effectively overcomes the above-described difficulties. This object is achieved, according to the present invention, by devising a cathode structure in which there is only a relatively low temperature differential, between the heater and the emitting surface of the cathode, when the device is in operation. For example, if the emitting portion of the cathode is to be operated at approximately 1500° C., according to this invention the heater need be operated at a temperature of only 2000° C. or below.

Another object of this invention is to devise a novel thoria cathode structure for high-power magnetrons.

The foregoing and other objects of the invention will be best understood from the following description of some exemplifications thereof, reference being had to the accompanying drawings, wherein:

Fig. 1 is a vertical section through a cathode-pole piece assembly according to the invention;

Fig. 2 is a section taken on line 2—2 of Fig. 1, on an enlarged scale;

Fig. 3 is a section taken on line 3—3 of Fig. 1;

Fig. 4 is a vertical section through a cathode assembly of modified construction;

Fig. 5 is a horizontal section taken on line 5—5 of Fig. 4; and

Fig. 6 is a perspective view of the upper portion of one of the members of Fig. 4, as it appears during the process of manufacture.

Now referring to Figs. 1-3, which illustrate one embodiment of a cathode structure according to this invention, a cylindrical metallic sleeve 6, of molybdenum or other suitable refractory metal, serves as a rigid supporting member for the emissive portion of the cathode, said sleeve preferably being machined from seamless tubular stock. A reticulated or screen-like mesh member 7 surrounds sleeve 6 and is rigidly secured to the same, preferably by being brazed or sintered thereto with molybdenum powder at a high temperature, on the order of 2300° C., for example. I have found that, when members 6 and 7 are joined in the above-described manner, screen member 7 is secured to sleeve 6 in an intimate manner. Sleeve 6 has a length in excess of that of screen member 7, and said screen member surrounds the central portion of said sleeve. Screen 7 supports and holds thereon a suitable electron-emissive coating 8 of thoria (thorium oxide) which is coextensive with said screen. In the above-described manner, emissive coating 8 is firmly held on sleeve 6.

50
 55

A plurality of equally-spaced, circumferentially-extending horizontal milled slots 9 (see Fig. 3), here shown as four in number, are provided in sleeve 6 slightly below the lower end of screen 7, the center lines of these slots all lying in a common horizontal plane. A similar plurality of equally-spaced, circumferentially-extending horizontal milled slots 10, four in number, are provided in sleeve 6 slightly above the upper end of screen 7, the center lines of these slots also all lying in a common horizontal plane. As illustrated in Fig. 3, there is only a small cross-section of metal between adjacent slots 9 and 10, so that the far larger part of the cross-sectional area of sleeve 6 in the planes of these slots consists of poorly-heat-conducting space. The operating temperature of the active or emitting portion 7-8 of cathode sleeve 6 is intended to be rather high, on the order of 1500° C., temperatures of this order being necessary in order to produce copious emission of electrons from the active material 8 utilized. It is desirable, for many reasons, to prevent heating of the end portions of sleeve 6, or of adjacent portions of the cathode structure, to this high temperature. The transverse slots 9 and 10, at the opposite ends of the central portion of sleeve 6, provide a heat choke, heat shield, or heat interrupter to minimize the conduction of heat, from the heated central portion of sleeve 6, to the end portions of said sleeve. Since the cross-section of heat-conducting metal between the end and central portions of supporting sleeve 6 is held to an absolute minimum by slots 9 and 10, the conduction of heat from the central to the end portions of said sleeve is limited to a very small amount, so that said end portions remain cool relative to said central portion, when said central portion is heated for electron emission.

A bottom support member 11, in the form of a hollow open-ended cylinder having an integral transversely-extending partition 11a therein, is secured as by brazing to the lower end portion of sleeve 6, the lower end face of said sleeve contacting the upper surface of partition 11a. The upper part of member 11 is reamed out to a larger diameter than the outer diameter of sleeve 6, to thereby provide an insulating annular space between the outer surface of said sleeve and the inner surface of said member in the region of slots 9, the outer surface of said sleeve firmly engaging the inner surface of said member in the region below said slots. The length of member 11 is such that the upper end thereof is located just slightly below the lower end of screen 7 and coating 8, and at its upper end member 11, which is machined from seamless tubular metallic stock, is provided with an integral outwardly-extending horizontal circular flange 11b, to serve as an end shield, preventing emission of electrons from coating 8 in undesired downward directions. Due to the facts that member 11 is metallically attached to sleeve 6 only in an area below and substantially distant from heat-choke slots 9, and that there is an annular space between the outer surface of said sleeve and the inner surface of said member substantially throughout the length of said member, the conduction of heat away from the emitting portion 7-8 of the cathode, by member 11, is very substantially reduced as compared to prior art structures. In fact, such conduction is reduced to substantially zero, or at least to a very low rate.

An upper support member 12, in the form of a hollow open-ended cylinder having an internal

annular projection 12a therein, is secured as by brazing to the upper end portion of sleeve 6, the upper end face of said sleeve contacting the lower surface of projection 12a. The lower part of member 12 is reamed out to a larger diameter than the outer diameter of sleeve 6, to thereby provide an insulating annular space between the outer surface of said sleeve and the inner surface of said member in the region of slots 10, the outer surface of said sleeve firmly engaging the inner surface of said member in the region above said slots. The length of member 12 is such that the lower end thereof is located just slightly above the upper end of screen 7 and coating 8, and at its lower end member 12, which is machined from seamless tubular material stock, is provided with an integral outwardly-extending horizontal circular flange 12b, to serve as an end shield, preventing emission of electrons from coating 8 in undesired upward directions. Member 12 is thus metallically attached to sleeve 6 only in an area above and substantially distant from heat-choke slots 10, and there is an annular space between the outer surface of said sleeve and the inner surface of said member substantially throughout the length of said member. Therefore, the conduction of heat away from the emitting portion of the cathode, by member 12, is very substantially reduced as compared to prior art structures, and is in fact reduced to substantially zero.

An elongated supporting cylindrical metallic sleeve 13 is firmly secured at its lower end, as by brazing, in and to the upper end of member 12, the lower end face of sleeve 13 contacting the upper face of projection 12a and the outer surface of sleeve 13 contacting the inner surface of member 12. Somewhat above the joint between sleeve 13 and member 12, said sleeve is provided with a plurality, for example three, of equally-spaced, circumferentially-extending horizontal milled slots 14, the center lines of these slots all lying in a common horizontal plane. Sleeve 13, similarly to members 6, 11 and 12, is machined from seamless tubular stock, and slots 14 serve as an additional heat choke or heat interrupter to further inhibit the conduction of heat from the hot central portion of sleeve 6 to the portions of the cathode structure above slots 14, thus preventing said last-named portions, which are sealed or fused to glass members, from reaching an undesirably high temperature.

The outer wall of sleeve 13 is provided with two horizontal annular shoulders near the upper end of said sleeve, and secured as by brazing at and to the uppermost of these shoulders is a sealing metallic sleeve 15 which is made of an alloy, such as Kovar, which is a metal commonly used for sealing to glass, the lower end surface of sleeve 15 contacting the horizontal face of the uppermost shoulder on sleeve 13. A hollow glass insulating sleeve 16 is fused at its lower end to the upper end of sleeve 15, while the upper end of sleeve 16 is in turn fused to the lower end of a second sealing metallic sleeve 17, also preferably made of Kovar.

The enlarged upper end of a rigid metallic solid rod heater conductor 18 passes through sealing sleeve 17, the upper end of said sleeve being hermetically sealed to the said end of conductor 18 around the periphery thereof, in order to hermetically seal and support the upper end of conductor 18 centrally of hollow members 6, 12, 13, 15, 16 and 17. A flexible lead wire 42 is electrically connected to the upper (exterior)

end of conductor 18. By means of sleeve 16, conductor 18 is electrically insulated from members 6, 12, 13 and 15. Rod 18 is preferably machined from solid stock, and terminates at its lower end, somewhat above slots 10, in an integral externally-threaded stud portion 19, which is more clearly shown in the embodiment of Fig. 4.

A bare or uncoated heater wire 20, of tungsten or other refractory metal, is coiled in the form of a helix and is secured and electrically connected to the lower end of rod 18 by having a plurality of turns at the upper end of said coil wound into or threaded into the thread grooves of stud portion 19, as clearly shown in Fig. 4. I have found that, by this threaded or wound coupling or joint between the heater wire 20 and rod 18, particularly if the heater wire is wound or threaded on an external thread, an extremely strong rigid joint or coupling may be made between said wire and said rod, without the necessity of any other fastening process, such as welding or brazing, being performed. Thus, a rather simple yet very strong joint between the upper end of the heater wire and rod 18 is obtained. The pitch of the turns of heater coil 20 is greater than the pitch of the threads or stud portion 19, so that the turns of said coil are compressed when wound on stud 19 and thus tend to spread apart after the joint between heater 20 and rod 18 is made, thus tending to cause the turns of coil 20 to bind in the threads more securely. Due to the rigidity of the joint between the upper end of heater 20 and rod 18, and also to the rigidity of the joint between rod 18 and sleeve 17, the upper end of the bare heater wire 20 is firmly held centrally of sleeve 6 and is effectively prevented from coming into contact therewith.

In order to secure the lower end of heater coil 20 in position, and to provide an electrical connection to the same, a plurality of turns at the lower end of said coil, somewhat below slots 9, are wound into or threaded into the thread grooves of an externally-threaded headless metallic member or stud 21, as clearly shown in Fig. 4, the pitch of the turns of said coil again being greater than the pitch of the threads on stud 21. An extremely rigid and strong joint, similar to that between the upper end of heater 20 and rod 18, is thus provided between the lower end of said heater and stud 21. Stud 21 is threaded throughout its length, and below the lower end of the heater it is threaded into a tapped aperture which is located centrally of partition 11a. When stud 21 is tightened in said aperture, the lower end of heater coil 20 is supported rigidly with respect to member 11. The heater coil 20 is made of sufficiently large diameter wire to be rather rigid in itself, and is supported rigidly at its upper and lower ends by threaded joints, without the use of any additional fastening means, in such a way that this bare wire heater coil is rigidly mounted centrally of sleeve 6, closely adjacent thereto yet spaced therefrom, without any possibility of its contacting said sleeve. Throughout the central portion of the length of sleeve 6, or the emitting portion 7-8 of the cathode, heater wire 20 is in effect hollow, or, in other words, there are no members of any kind to inhibit the free flow of heat from said heater wire to sleeve 6 which supports coating 8.

Since heater wire 20 is in effect hollow throughout the emitting portion 7-8 of the cathode, and since the end shields or members 11 and 12 are mounted in substantially non-heat-conducting

relationship with respect to portion 7-8 of the cathode, as above described, there is extremely good conduction of heat from the heater to the cathode, and extremely poor conduction of heat away from the exterior of the cathode. Therefore, during operation of the cathode there is only a low temperature difference between the heater 20 and the cathode 6. For example, to operate the cathode at 1500° C., the heater need be operated at a temperature of only 2000° C. or below. The fact that the heater wire in this construction is bare, and not covered with a heat-insulating or poorly-heat-conducting coating, also increases the conduction of heat from the heater to the cathode.

Due to the rigid mounting of the heater 20 as above described, bare or uncoated heater wire may be used without danger of short-circuits. Therefore, the cathode may be run at high operating temperatures, above the temperature of breakdown for insulating coatings used in the prior art on heater wires, since such breakdown temperature was a limiting factor for previous structures.

Furthermore, due to the rigid mountings at opposite ends of the heater wire, combined with the longitudinal rigidity of the supporting structure, substantially no movement of the heater can occur in the longitudinal direction.

In order to provide a common heater-cathode electrical connection, a metallic ring member 22 is hermetically sealed around the periphery of sleeve 13, at the lowermost of the two horizontal annular shoulders thereon. A flexible lead wire 23 is electrically connected, as by soldering, to member 22. When a source of heater voltage is applied between leads 42 and 23, current flows through rod 18, heater 20, stud 21, support member 11, sleeve 6, support member 12, sleeve 13, and ring member 22, such current being converted into heat in heater 20, raising the temperature of sleeve 6 to the temperature of thermionic emission for coating 8.

In order to provide a cathode-pole piece assembly suitable for use in a magnetron, an inverted cup-shaped member 24, of the material known as Kovar for example, is hermetically sealed horizontally around the periphery of ring member 22, and extends downwardly therefrom. The lower end of member 24 is fused and hermetically sealed to the upper end of a glass insulating sleeve 25, the lower end of which is fused and hermetically sealed to the upper end of a Kovar sleeve 26. The lower end of sleeve 26 is in turn hermetically sealed into the central portion of an inverted frusto-conical pole piece 27.

In order to mount the assembly as above described in a magnetron to serve as the cathode thereof, pole piece 27 is hermetically sealed into a magnetron envelope, as more fully described in the copending Brown application, Ser. No. 742,541, filed April 19, 1947. The glass sleeve 25 insulates the cathode sleeve 13 and lead 23 from the envelope or anode of the magnetron and pole piece 27.

Figs. 1-3 disclose a cathode structure the principal elements 6, 11, 12 and 13 of which are machined from seamless tubular metallic stock. It is within the scope of this invention to provide a structure in which corresponding elements are stamped out of sheet stock and are thereafter rolled to cylindrical shape, thus providing a substantially cheaper structure than that previously disclosed. Figs 4-6 illustrate such a sheet metal construction, and in these figures, parts the same

as those previously described are denoted by the same reference numerals.

An elongated metallic sleeve 28 is stamped out of refractory sheet metal and thereafter is rolled into open-ended cylindrical shape, as indicated in Fig. 6, until its edges abut to form a longitudinal seam 29. A horizontal annular shoulder 30 is provided at the upper end of sleeve 28; this shoulder corresponding to the one which ring member 22 contacts in Fig. 1. A screen member 6 surrounds and is fastened to sleeve 28 in the same manner as in the embodiment previously described; this screen member properly supporting an emissive coating 8 of the type previously described.

A plurality, for example three, of equally-spaced, circumferentially-extending horizontal heat-choke slots 31 are punched through sleeve 28 slightly below the lower end of screen 7, the center lines of these slots all lying in a common horizontal plane. A similar plurality, for example three, of equally-spaced, circumferentially-extending horizontal heat-choke slots 32 are punched through sleeve 28 slightly above the upper end of screen 7, the center lines of these slots all lying in a common horizontal plane. A third group of similar horizontal heat-choke slots 33 is punched through sleeve 28 a substantial distance above the slots 32, while a fourth group of similar horizontal heat-choke slots 34 is punched through sleeve 28 somewhat above slots 33, the slots of each group lying in a common horizontal plane and the slots of group 34 preferably being displaced angularly with respect to those of group 33. As shown in Fig. 5, there is only a very small cross-section of heat-conducting metal between adjacent slots in each group.

A lower sheet metal cylindrical spacing sleeve 35 surrounds and is brazed to sleeve 18 at the lower end thereof. A bottom sheet metal end cap 36, rolled in the form of a cylindrical sleeve, surrounds and is brazed to the outer surface of sleeve 35, sleeve 36 having a length such that it terminates just below the lower end of screen 7. In order to provide a bottom end shield for the cathode, a piece of round wire 37 surrounds and is brazed to cap 36 at the upper end thereof, to prevent emission of electrons in undesired downward directions.

A similar upper sheet metal end cap structure is provided, including an upper sheet metal cylindrical spacing sleeve 38 which surrounds and is brazed to sleeve 18 above slots 32. An upper sheet metal end cap 39, rolled in the form of a cylindrical sleeve, surrounds and is brazed to the outer surface of sleeve 38, sleeve 39 having a length such that it terminates just above the upper end of screen 7. A piece of round wire 40 surrounds and is brazed to cap 39 at the lower end thereof, to prevent emission of electrons in undesired upward directions. Spacing members 35 and 38 provide the necessary and desirable insulating annular space between sleeve 28 and the respective cap members 36 and 39, in the region of the respective slots 31 and 32. End caps 36 and 39, like the similar elements 11 and 12 in Fig. 1 are metallically attached to sleeve 28 only in areas substantially distant from the respective heat-choke slots 31 and 32, on the sides of said slots respectively opposite to the central portion of the cathode, and there are corresponding annular spaces between the outer surface of the sleeve 28 and the inner surfaces of caps 36 and 39, substantially throughout the length of such caps.

Therefore, the conduction of heat away from the emitting portion 7-3 of the cathode, by caps 36 and 39, is reduced to substantially zero.

The upper end of heater coil 20 is joined to rod 18 by means of threaded stud portion 19, in the manner previously described, while rod 18 is mounted centrally in sleeve 28 in the same manner as previously described.

A horizontal bushing member 41, having a central tapped aperture therein, is brazed inside the sleeve 28 near the lower end thereof. The lower end of coil 20 is threaded secured to a stud 21, in the manner previously described, said stud being threaded externally throughout its length and threaded tightly into the central tapped aperture in bushing 41.

As described above in connection with the previous embodiment, in this way the heater coil 20 is supported rigidly at its upper and lower ends by these threaded joints, in such a way that this bare wire heater coil is rigidly mounted centrally of sleeve 28, closely adjacent thereto yet spaced therefrom, without any possibility of its contacting said sleeve. Moreover, these joints at the upper and lower ends of the heater coil 20 are made without the necessity of doing any welding or brazing, or of providing any additional fastening means.

As in the embodiment of Fig. 1, due to the construction of the cathode according to this invention, there is extremely good conduction of heat from the heater to the cathode, and extremely poor conduction of heat away from the exterior of the cathode. During operation of the cathode there is only a low temperature difference between the heater and the cathode.

Electrical connections to the heater and cathode of Figs. 4-6 are made in the same manner as in the previously-described embodiment. A cathode-pole piece assembly is preferably constructed from the rolled sheet metal embodiment of Figs. 4-6 in exactly the same way as described previously for the machined embodiment of Figs. 1-3.

Of course, it is to be understood that this invention is not limited to the particular details as described above, as many equivalents will suggest themselves to those skilled in the art. It is accordingly desired that the appended claims be given a broad interpretation commensurate with the scope of this invention within the art.

What is claimed is:

1. An indirectly-heated cathode structure, comprising a cylindrical supporting sleeve of refractory material, an electron-emissive coating supported on the outside of said sleeve, a rigid metallic member insulatingly supported substantially centrally inside said sleeve and spaced from the inner wall thereof, and a bare wire heater having one end thereof secured to said member and its opposite end threadably fastened with respect to one end of said sleeve, said heater being disposed opposite said coating and being spaced throughout its length from the inner wall of said sleeve.

2. An indirectly-heated cathode structure, comprising an elongated cylindrical supporting sleeve, an electron-emissive coating supported on the outside of said sleeve over a portion of its length intermediate the ends thereof, said sleeve being provided with means for inhibiting the flow of heat from said portion to the two end portions thereof, a rigid metallic member insulatingly supported substantially centrally inside said sleeve and spaced from the inner wall thereof, and a

bare wire heater having one end thereof secured to said member and its opposite end rigidly threadably fastened with respect to one end of said sleeve, said heater being disposed opposite said coating and being spaced throughout its length from the inner wall of said sleeve.

3. An indirectly-heated cathode structure, comprising a cylindrical supporting sleeve of refractory metal, an electron-emissive coating supported on the outside of said sleeve, a metallic member insulatingly supported substantially centrally inside said sleeve, a supporting conducting member extending transversely across the interior of said sleeve near one end thereof, a bare wire heater having one end thereof threadably secured to said metallic member, and means rigidly securing the opposite end of said heater to said supporting member, said heater being disposed opposite said coating and being spaced throughout its length from the inner wall of said sleeve.

4. An indirectly-heated cathode structure, comprising a cylindrical supporting sleeve of refractory metal, an electron-emissive coating supported on the outside of said sleeve, a rigid metallic member insulatingly supported substantially centrally inside said sleeve and spaced from the inner wall thereof, said member having a threaded portion at one end thereof, and a bare wire helical heater coil having a plurality of turns at one end thereof wound into the thread grooves of said threaded portion and having its opposite end rigidly metallically fastened with respect to one end of said sleeve, said coil being disposed opposite said coating and being spaced throughout its length from the inner wall of said sleeve.

5. An indirectly-heated cathode structure, comprising a cylindrical supporting sleeve of refractory metal, an electron-emissive coating supported on the outside of said sleeve, a rigid metallic member insulatingly supported substantially centrally inside said sleeve and spaced from the inner wall thereof, a bare wire helical heater coil having one end thereof rigidly secured to said member, and a threaded member at the opposite end of said heater coil into the thread grooves of which a plurality of turns at said opposite end of said coil are wound, said threaded member being rigidly metallically fastened with respect to one end of said sleeve, said coil being disposed opposite said coating and being spaced throughout its length from the inner wall of said sleeve.

6. An indirectly-heated cathode structure, comprising a cylindrical supporting sleeve of refractory metal, an electron-emissive coating supported on the outside of said sleeve, a rigid metallic member insulatingly supported substantially centrally inside said sleeve and spaced from the inner wall thereof, said member having a threaded portion at one end thereof, a bare wire helical heater coil having a plurality of turns at one end thereof wound into the thread grooves of said threaded portion, and a threaded member at the opposite end of said heater coil into the thread grooves of which a plurality of turns at said opposite end of said coil are wound, said threaded member being rigidly metallically fastened with respect to one end of said sleeve, said coil being disposed opposite said coating and being spaced throughout its length from the inner wall of said sleeve.

7. An indirectly-heated cathode structure, comprising a cylindrical supporting sleeve of refractory metal, an electron-emissive coating sup-

ported on the outside of said sleeve, a rigid metallic member insulatingly supported substantially centrally inside said sleeve and spaced from the inner wall thereof, a supporting conducting member extending transversely across the interior of said sleeve near one end thereof, a bare wire helical heater coil having one end thereof rigidly secured to said first-named member, and a threaded member at the opposite end of said heater coil into the thread grooves of which a plurality of turns at said opposite end of said coil are wound, said threaded member being threaded into said supporting member, said coil being disposed opposite said coating and being spaced throughout its length from the inner wall of said sleeve.

8. An indirectly-heated cathode structure, comprising a cylindrical supporting sleeve of refractory metal, an electron-emissive coating supported on the outside of said sleeve, a rigid metallic member insulatingly supported substantially centrally inside said sleeve and spaced from the inner wall thereof, said member having a threaded portion at one end thereof, a supporting conducting member extending transversely across the interior of said sleeve near one end thereof, a bare wire helical heater coil having a plurality of turns at one end thereof wound into the thread grooves of said threaded portion, and a threaded member at the opposite end of said heater coil into the thread grooves of which a plurality of turns at said opposite end of said coil are wound, said threaded member being threaded into said supporting member, said coil being disposed opposite said coating and being spaced throughout its length from the inner wall of said sleeve.

9. An indirectly-heated cathode structure, comprising an elongated cylindrical supporting sleeve of refractory metal, an electron-emissive coating supported on the outside of said sleeve over a portion of its length intermediate the ends thereof, said sleeve being provided with means for inhibiting the flow of heat from said portion to the two end portions thereof, a rigid metallic member insulatingly supported substantially centrally inside said sleeve and spaced from the inner wall thereof, said member having a threaded portion at one end thereof, a bare wire helical heater coil having a plurality of turns at one end thereof wound into the thread grooves of said threaded portion, and a threaded member at the opposite end of said heater coil into the thread grooves of which a plurality of turns at said opposite end of said coil are wound, said threaded member being rigidly metallically fastened with respect to one end of said sleeve, said coil being disposed opposite said coating and being spaced throughout its length from the inner wall of said sleeve.

10. An indirectly-heated cathode structure, comprising an elongated cylindrical supporting sleeve of refractory metal, an electron-emissive coating supported on the outside of said sleeve over a portion of its length intermediate the ends thereof, said sleeve being provided with means for inhibiting the flow of heat from said portion to the two end portions thereof, a pair of opposite metallic shield members secured to the outer surface of said sleeve adjacent the respective opposite end portions thereof and on the sides of the respective inhibiting means remote from said first-named portion of said sleeve, said members each extending toward said first-named portion of said sleeve and being spaced from the

outer surface thereof, and heater means mounted inside said sleeve.

11. An indirectly-heated cathode structure, comprising an elongated cylindrical supporting sleeve of refractory metal, an electron-emissive coating supported on the outside of said sleeve over a portion of its length intermediate the ends thereof, said sleeve having therein at opposite ends of said portion slots for inhibiting the flow of heat from said portion to the two end portions thereof, a pair of opposite metallic shield members secured to the outer surface of said sleeve adjacent the respective opposite end portions thereof and on the sides of the respective slots remote from said first-named portion of said sleeve, said members each extending toward said first-named portion of said sleeve and being spaced from the outer surface thereof, and heater means mounted inside said sleeve.

12. An indirectly-heated cathode structure, comprising an elongated cylindrical supporting sleeve of refractory metal, an electron-emissive coating supported on the outside of said sleeve over a portion of its length intermediate the ends thereof, said sleeve being provided with means for inhibiting the flow of heat from said portion to the two end portions thereof, a pair of opposite metallic shield members secured to the outer surface of said sleeve adjacent the respective opposite end portions thereof and on the sides of the respective inhibiting means remote from said first-named portion of said sleeve, said members each extending toward said first-named portion of said sleeve and being spaced from the outer surface thereof, a rigid metallic member 20 insulatingly supported substantially centrally in-

5 side said sleeve and spaced from the inner wall thereof, and a bare wire heater having one end thereof rigidly secured to said member and its opposite end rigidly threadably fastened with respect to one end of said sleeve, said heater being disposed opposite said coating and being spaced throughout its length from the inner wall of said sleeve.

10 13. A cathode structure comprising a cathode cylinder, a heater coil positioned within said cathode structure, and a coil support comprising a threaded conductor, a plurality of turns of said coil being wound into the thread grooves of said conductor.

15 14. A cathode heater structure comprising a heater coil, and a coil support comprising a threaded conductor, a plurality of turns of said coil being wound into the thread grooves of said conductor.
